HONING TOOL

Carl E. Beck, San Francisco, Calif.

Application March 25, 1946, Serial No. 656,857

6 Claims. (Cl. 51—184.3)

1

This invention relates to honing tools and more particularly to means for abrasive finishing small holes.

Among the objects of the invention is the provision of means for finishing holes to fine tolerances.

Another object is the provision of means for accurately and positively advancing the abrasive element with micrometric precision.

Another object is to adapt a single tool to various sizes of relatively small holes.

A further object is to protect the mandrel from abrasive wear.

After heat treating a piece of steel having holes therein, the holes are shrunken to a smaller size and often distorted out of round. The metal is then too hard to drill or ream accurately, but can be abraded or honed to precision by the present invention.

Other objects and advantages will appear as the description progresses. In the specification and the accompanying drawings the invention is disclosed in its present preferred form. But it is to be understood that it is not limited to this form, because it may be embodied in modifications within the spirit of the invention as defined in the claims following the description.

In the one sheet of drawings:

Fig. 1 is a longitudinal vertical section of a honing tool constructed in accordance with this invention, on the line 1—1, Fig. 2.

Fig. 2 is a plan view from above of the same, partially broken away to disclose the underlying bar retracting spring.

Fig. 3 is an end view of the same.

In detail the structure shown in Fig. 1 comprises the cylindrical mandrel 1, of the desired diameter and heat treated and ground to the desired size, up to the shoulder at 2, of the head 3. The head has the external threaded portion, upon which vernier sleeve 4 is threaded and has the graduated scale 5 reading with the index 6 on the head. This sleeve has the knurled portion 1.

The exterior of the head 3 may be parallel as shown for chucking in a lathe, or it may be tapered for use in a drill press or other reciprocating drive. The head is center bored at 8 up to the shoulder 2, and is closed at the end by the plug 9 threaded therein.

The mandrel 1 has the longitudinal slot 11 milled therein from the outer end into the head 3, to meet the center bore 8. The plunger 12 has the stem 13, telescoping into the expansive spring 14, interposed between the plunger and the plug 9.

The plunger retractor 15 is slideable on the head 3, and has the annular internal groove 16, engaging the stud 17 threaded into the plunger 12 through the hole 18 in the retractor. Acting through this stud, the spring 13 maintains the retractor under spring tension against the vernier

2

sleeve 5. The forward end of the plunger 12 is transversely reduced and has the upstanding pin 19.

Referring to Fig. 2, the bottom of the slot 11 has the interspaced cams 20, 21, fixed therein by studs passing through the body of the mandrel 1 and riveted in countersunk holes therein. The spring detent 22 is also fixed to the bottom of this slot and held by the rivet 23, similarly riveted to the body of the mandrel. This detent consists of a piece of hard wire bent back upon itself to form a loop held by the rivet 23, with its projecting extensions adjacent the sides of the slot 11. The ends of these extensions are bent upward at 25 and directed toward the open end of the slot 11.

The hone holder, Fig. 1, consists of the bar 26 transversely milled away to form the overhanging end 27 with a hole therethrough engaging the pin 19 of the plunger 12. The inclined cam faces at 28, 29, ride on the cams 20, 21 to extend and retract the bar 26 relative to the diameter of the mandrel 1. The longitudinal rib 30, has the lateral lugs at 31 on its opposite sides, which engage beneath the extensions of the wire detent 22 to normally retract the bar 26 into the slot 11.

The hone 32 is shaped to removably fit into a longitudinal groove in the outer face of the bar 26, flush with the periphery of the mandrel 1, see Fig. 3. This hone is formed of a suitably bound grit of the desired grade adapted to the type of metal to be abraded.

The bar 26 is assembled into the slot 11, by dropping it into the slot with the lugs at 31 ahead of the upturned ends 25 of the wire detent 22. Then the bar is forced backwardly. As the bar is moved rearwardly, the upturned ends 25 of the detent ride upwardly over the lugs and urge the bar outwardly on to the inclined cams at 20, 21.

The segmental sleeve 33 telescopes over the length of the mandrel 1, up to the shoulder 2. This sleeve is made of a hard heat treated alloy and ground to the diameter desired. Its function is to enable the adjustment of the mechanism to a range of sizes by substituting sleeves such as 33. In the larger sizes a thicker hone 32 can be substituted to match the diameter of the sleeve 33. This sleeve has the further advantage that it takes the lapping wear incidental to waste grit that may accumulate between it and the inner diameter of the hole being lapped, thus saving the mandrel from such destructive wear.

This invention operates substantially as follows: The head 3 is chucked in the drill press or other form of drive. The swiveled retractor 15 is manually retracted, which lowers the bar 26 on the cams 20, 28 and 20, 29 by the backward push of the stud 17 on the plunger 12, against the tension of the spring 14, the tension of which may be regulated by the screw plug 9.

The end of the mandrel is then inserted in the hole to be honed and the retractor 15 is released until it abuts the vernier sleeve 4 that has been adjusted to hone the hole to the calibrated size.

While the mandrel and hone 32 are being rotated, the drill press head is reciprocated up and down to cause a lapping action of the hone against the wall of the hole being honed. This prevents concentric scoring of this wall and insures a uniform texture of the wall. Occasionally the swivel retractor 15 is lifted to slightly release the hone from the wall of the hole to clear accumulated waste grit and abraded metal, which collects in the space between the edges of the segmental sleeve 33 and the slot 11.

When the swivel retractor 15 is released the spring 14 pushes the bar 26 up the inclined cams 20, 21 and forces the hone gently against the wall of the hole, permitting it to perform its abrasive function.

Average mechanical ability is all that is required to operate this invention, after the vernier adjustment at 5 is set to the desired calibration, preventing an oversize honing of the hole.

In this art three eighths of an inch is considered a small hole, but by appropriate precision in constructing this invention smaller sizes can be so honed, because of the simplicity and direct action of the structure of the invention. It is equally adaptable to the honing of such holes or cylinder bores in the larger sizes.

Having fully described this invention and its mode of operation, what I claim and desire to secure by Letters Patent is:

1. A honing tool comprising a mandrel having a head with a center bore therein, and a longitudinal slot in said mandrel open to said centerbore and having an inclined bottom portion; a bar slideable in said slot and having inclined portions slideable on said bottom; a hone supported on said bar, a vernier stop threaded on said head; a plunger slideable in said head and engaging said bar and having a stud extending through said slot; a plunger retractor slideable on said head and engaging said stud; and a spring in said center bore and bearing against said plunger, said vernier stop acting to limit the forward movement of said plunger retractor and cooperating therewith to regulate the extent of outward movement of the said bar and hone.

2. A honing tool comprising a mandrel having a head with a center bore therein, and a longitudinal slot in said mandrel and extending into said centerbore; a pair of cams in the bottom of said slot; a bar slideable in said slot and having cam portions engaging said cams; a hone supported on said bar, resilient means normally extending said bar into said slot; a vernier stop threaded on said head; a plunger slideable in said head and engaging said bar and having a stud extending through said slot; a plunger retractor slideable on said head and engaging said stud; and a spring in said centerbore and bearing against said plunger, said vernier stop acting to limit the forward movement of said plunger retractor and cooperating therewith to regulate the extent of outward movement of the said bar and hone.

3. A honing tool comprising a mandrel having a head with a centerbore therein, and a longitudinal slot in said mandrel open to said centerbore; interspaced inclined portions on the bottom of said slot; a bar slideable in said slot and having cams engaging said inclined portions; a hone supported on said bar, lugs on said bar interme-

diate said cams; a resilient means fixed to said bottom and engaging said lugs; a vernier stop threaded on said head; a plunger slideable in said centerbore and engaging said bar and having a stud extending through said slot; a plunger retractor slideable on said head and engaging said stud; and a spring in said centerbore and bearing against said plunger, said vernier stop acting to limit the forward movement of said plunger retractor and cooperating therewith to regulate the extent of outward movement of the said bar and hone.

4. A honing tool comprising a mandrel having a head with a centerbore therein, and a longitudinal slot in said mandrel open to said centerbore and having an inclined bottom portion; a bar slideable in said slot and having inclined portions slideable on said bottom portion; a hone supported on said bar, a vernier stop threaded on said head; a plunger slideable in said head and engaging said bar and having a stud extending through said slot; a plunger retractor slideable on said head and engaging said stud; a spring in said centerbore and bearing against said plunger; said vernier stop acting to limit the forward movement of said plunger retractor and cooperating therewith to regulate the extent of outward movement of the said bar and hone, and a segmental sleeve removably surrounding said mandrel.

5. A honing tool comprising a mandrel having a head with a centerbore therein and a longitudinal slot in said mandrel open to said centerbore and having an inclined bottom portion; a bar slideable in said slot and having inclined portions slideable on said bottom portion; a hone supported on said bar, a vernier stop threaded on said head; a plunger slideable in said head and engaging said bar and having a stud extending through said slot; an annular plunger retractor having an internal groove engaging said stud; a spring in said centerbore and bearing against said plunger, said vernier stop acting to limit the forward movement of said plunger retractor and cooperating therewith to regulate the extent of outward movement of the said bar and hone.

6. A honing tool comprising a mandrel having a head with a centerbore therein and a longitudinal slot in said mandrel open to said centerbore and having an inclined bottom portion; a honing bar slideable in said slot and having inclined portions slideable on said bottom portions; a hone supported on said bar, a vernier stop threaded on said head; a plunger slideable in said head and engaging said bar and having a stud extending through said slot; a plunger retractor slideable on said head and having an internal groove engaging said stud; a spring in said centerbore and bearing against said plunger; said vernier stop acting to limit the forward movement of said plunger retractor and cooperating therewith to regulate the extent of outward movement of the said bar and hone, and a segmental sleeve removably surrounding said mandrel on the opposite sides of said slot.
